UNITED STATES PATENT OFFICE

WILLIAM G. CALKINS, OF DETROIT, MICHIGAN, ASSIGNOR TO CHRYSLER CORPORATION, OF DETROIT, MICHIGAN, A CORPORATION OF DELAWARE

VALVE TAPPET

Application filed June 7, 1928. Serial No. 283,674.

This invention relates to a valve tappet and is illustrated as embodied in a valve tappet for use in internal combustion engines.

In the manufacture of internal combustion engines it is desirable to rotate the valve tappet with respect to its operating cam so that the cam engaging face of the tappet is worn even and smooth. Heretofore the tappet has been rotated by positioning the axis 10 of the tappet out of line with the operating cam so that the cam will strike the engaging face at one side of its center thereby turning the tappet on its axis.

An important object of this invention is 15 to provide a means for rotating the tappet which is inexpensive and which may be used independent of the offset arrangement of the tappet with respect to the operating cam or used in conjunction therewith.

Another object of the invention is to rotate 20 the valve tappet by the lubricant pressure, preferably by forcing the lubricant past a serrated portion of the tappet.

A further object of the invention in the 25 preferred embodiment of my invention is to arrange the serrations such that the lubricant pressure forces the tappet upwardly away from the operating cam and against the valve stem to take up the clearance usually 30 left between the valve stem and the tappet.

Other objects and features of the invention including various desirable details of construction will be apparent from the following 35 description of one illustrated embodiment shown in the accompanying drawings, in which:

Fig. 1 is a side elevation of a portion of a 40 valve mechanism for an internal combustion engine, parts being shown broken away and in section.

Fig. 2 is a sectional view taken on line 2-2 of Fig. 1.

Fig. 3 is a sectional view on line 3-3 of 45 Fig. 1, parts being shown in elevation.

Fig. 4 is a side elevation of a tappet showing one form of serrations in the periphery of the tappet.

Fig. 5 is a sectional view on line 5-5 of 50 Fig. 4.

Fig. 6 is a side elevation of a tappet showing spiral serrations.

Fig. 7 is a side elevation of a tappet in which tapered serrations are provided in the outer periphery thereof, a portion of the tappet being broken away and shown in section.

Fig. 8 is a sectional view through a tappet showing a modified form of the serrations which may be used with any one of the forms shown in Figs. 4, 6 and 7.

Referring to the illustrated embodiment of my invention, a valve operating mechanism is shown in Fig. 1 including a camshaft 10, valve tappet guides 12 and valve tappets 14.

The valve tappet guides are shown formed in a single member 16 which is bolted to the side of the cylinder block by bolts 18. A longitudinal passage 20 is formed in the member 16 and its inner wall intersects with

each of the openings for the valve tappets in the guides 12 so that when the valve tappets are in position a portion of their outer periphery extends into the passage 20 as shown in Fig. 2. Connections 22 and 24 are shown

at the opposite ends of the passage, one connection 22 to admit a lubricant under pressure to the passage and the other 24 to conduct the lubricant to the various parts of the engine to be lubricated. Thus it will be apparent that lubricant under pressure con-

tinually flows through the passage 20 in engagement with a portion of the valve tappet stem.

The camshaft is journaled in a bearing 26 and is provided with cams 28 adapted to reciprocate the tappet for lifting or closing the valves 30. The camshaft may be driven in the usual manner.

On the outer periphery of the valve tappet stem I have provided a plurality of serrations 32. In Figs. 3 and 4 the serrations have been shown as vertical grooves. The lubricant is received in these grooves and as it flows through the passage 20, and the tappet is carried with the lubricant and rotated thereby.

In the form of my device shown in Fig. 6 the serrations have been shown in the form of spiral grooves 34. As the lubricant flows past these grooves the pressure is directed upwardly forcing the tappet upwardly against

the lower end of the valve stem. In the form shown in Fig. 7 the serrations 36 are wedge shaped with the large end of each serration deeper at the top than at the bottom. This form also provides a means lifting the tappet by the lubricant pressure.

If desired the serrations in any of the forms shown may be formed as shown in Fig. 8. The one side of the serrations next to the 10 inlet side of the lubricant port may be tapered from the outer periphery of the tappet to the bottom of the groove as indicated by the numeral 38. The other side of the wall is formed radial as at 40 to form a shoulder 15 against which the lubricant under pressure forces the tappet in an angular direction.

It will be understood that various changes including size and arrangement of parts may be made without departing from the spirit of 20 my invention and it is not my intention to limit its scope other than by the terms of the appended claims.

What I claim is:

1. A tappet of the class described comprising a stem portion and a cam engaging portion, means for lubricating the stem portion, and means on the periphery of said stem for rotating the tappet by the lubricant pressure on the same.
2. A tappet of the class described comprising a stem portion and a cam engaging portion, means for flowing liquid on the stem portion, and means on the periphery of said stem adapted to urge said tappet upwardly 35 and angularly by the flow of liquid under pressure past the periphery of said stem.
3. A construction of the class described comprising, in combination, a plurality of valve tappets arranged in alignment, and 40 each provided with serrations in the periphery of their stems, a support having openings to receive the valve tappet stems, and a lubricant passage in said support communicating with the openings in said support.
4. A construction of the class described comprising, in combination, valve tappet guides, valve tappets in said guides, a lubricant passage adjacent said tappets, a portion of the periphery of said tappets extending 45 into said passage, and means on the periphery of said tappets adapted to be effected for angular movement by the flow of lubricant thru said passage.
5. A construction of the class described comprising, in combination, valve tappet guides, valve tappets in said guides, a lubricant passage adjacent said tappets and communicating with a portion of the periphery of 55 said tappets, and means on the periphery of said tappets adapted to urge said tappets upwardly and angularly by the flow of lubricant under pressure past the periphery of said tappets.
6. A construction of the class described comprising an engine having a lubricating 65

system and a plurality of tappets and means for moving said tappets in at least one direction by the force of the oil in said lubricant system.

7. A construction of the class described comprising an engine having a fluid pressure system and a plurality of tappets and means for turning said tappets through the force of the pressure in said system.
